UNITED STATES PATENT OFFICE

2,508,829

SNOW CONVEYER

Armand Lamy, Montreal, Quebec, Canada, assignor of one-half to Ubald Boisvert, Montreal, Quebec, Canada

Application April 6, 1948, Serial No. 19,251
In Canada April 21, 1947

4 Claims. (Cl. 37—45)

1

The present invention relates to snow handling means and, more particularly, snow gathering and conveying means for road clearing purposes.

The primary object of the invention resides in the provision of snow conveying means of highly efficient nature for the purpose in view.

Another important object is the provision of a snow conveyor especially calculated to remove drifted or banked snow from the edges of roads and streets.

A further object contemplates a self-driven snow conveying device adapted to be propelled by a suitable vehicle for clearing rapidly snow banks and drifts and loading the resulting snow into a suitable vehicle.

Still another object concerns a snow conveyor of the character defined which is rugged, of simple construction and, hence, easy to service.

A still further object of the invention envisages a snow conveying unit of versatile character, light in weight and relatively inexpensive.

Other objects and advantages of the invention will become apparent, or be pointed out further, during the description to follow.

As an example, and for purposes of illustration only, an embodiment of the invention is shown in the annexed drawings wherein:

Figure 1 is a front elevational view of the apparatus according to the invention;

Figure 2 is a transverse vertical section taken through said apparatus;

Figure 3 is a plan view thereof;

Figure 4 is a side elevation view with the gear box cover broken away to show the arrangement of the gear train;

Figure 5 is a longitudinal vertical section taken through the apparatus;

Figure 6 is a horizontal section taken through the apparatus to show the snow conveying means;

Figure 7 is a front elevation of one snow comminuting impeller;

Figure 8 is a side elevation thereof; and

Figure 9 is a vertical section taken on line 9—9 of Figure 5.

Referring to the drawings wherein similar reference characters represent corresponding parts throughout, the reference letter C indicates generally the main casing of the apparatus, which casing is constituted of side walls 10, bottom wall 11 and a back wall 12, the casing being adapted to be supported in front of a suitable propelling vehicle and resting on the ground over runners or the like 13. The casing C is supported as a complete unit, from the truck or other

2

suitable vehicle indicated by the letter T, by means of a pair of arms 15 extending rearwardly from the casing, at the sides thereof, said arms being bushed at 16 over shaft 18 secured directly onto the frame F of said truck. (See Figures 3 and 4.) For raising the casing from the ground, whenever it is undesirable to let said casing rest on its runners 13, means are provided for performing this raising operation, which means consist of brackets 17 pivoted to the shaft 18, said brackets being further clamped under the vehicle front axle A (Fig. 2) and formed with an end offset projection 22, said projection having pivoted thereto a hydraulic cylinder or the like

19 connected also to the forward end of arm 15 and communicating, by means such as the pipes 20, with a source of hydraulic pressure on the vehicle. Consequently the piston rod 21 extending from the cylinder can be extended or retracted at will so as to elevate or lower the casing end of the arms 15 and, thus, move said casing correspondingly in order that it may cope with unexpected or particular conditions of the roads to be cleared.

25 As shown to advantage in Figures 1, 2 and 5, the open-fronted casing is provided with a vertical partition 25 extending across, and adjacent to, the mouth of said casing so as to define with the rear wall 12 and the top wall 26 an enclosure

30 sub-divided into a plurality of separate chambers as will be explained later on. For snow admitting purposes, however, the partition 25 is provided with a bottom side rectangular aperture 27, said aperture opening into a longitudinal cylindrical duct 30 formed by the tubular member 31 extending completely across the side walls 10 as shown in Figures 5 and 6.

35 A shaft 35, longitudinally journaled in the center of the ducts in bearings 36 mounted in the side walls 10, carries a strip 37 wound helicoidally therearound in edgewise position, said strip and shaft forming together an endless archimedean screw or worm W. This worm is actuated by means of a gear 38 mounted on an extension of the shaft 35 projecting outside one side wall 10

40 which gear meshes with an idler gear 39, said idler gear being driven by the drive pinion 40 from a source of power to be described later on. The object of the worm just described is to displace 45 from left to the right the snow entering the duct 30 through the aperture 27; for that purpose the pitch of the helix as well as the direction of rotation are calculated with that object in view.

To the right end of the duct 30 there is connected a vertical discharge cylindrical duct 50

which is open, at its upper end, above the casing top 26. This discharge duct 50 is adapted to receive an endless screw or worm 51, in all respects similar to the worm W, this second worm 51 being mounted on a shaft 52 driven from the shaft 35 through the intermediary of bevel gears 53, 58 disposed in a gear-box 54 properly supported on the floor 11 of the casing by means of a pillar or the like 55. This gear-box serves also to locate the shaft 52 in the center of the duct 50 and to journal the same at its lower end, the upper end being journalled into a bearing 56 properly supported by the spider 57. The said spider is in turn supported within a pipe extension 60 having a lower flange 61 rotatably mounted over a ball bearing 62 carried at the top of casing 10; the extension 60 is held in alignment with the duct 50 by means of a flanged collar 63 so as to be rotatable with respect to the said duct for a purpose to be explained later on.

Immediately below the duct 50, beyond the worm W, a blade impeller 65 is provided on each side of the gear-box 54, said impeller as shown in Figure 9 consisting of diametrically aligned blades positioned in a common plane on each side of the box 54. Said impellers are intended to displace the snow carried by the worms W so that said snow may be taken up by the worm 51 and carried upwardly in the duct 50 and pipe 60. At the top of said pipe the snow is discharged through an adjustable elbow E which consists of a number of pipe sectors 67 arranged in telescopic fashion and adapted to retract more or less one within the other. This adjustment is effectuated, as is obvious, by means of the arcuate bar 68 shown in Figure 1.

For the purpose of comminuting, or disintegrating, ice formations, packed snow lumps or other hard agglomeration which may tend to prevent the free flowing of snow into the aperture 27, means are provided in front of said aperture in the form of comminuting rotary blades disposed across the lower part of the casing mouth. For that purpose, shafts 70 are spacedly supported horizontally across the casing and suitably mounted in bearings on the side walls 10. The said shafts extend to the left past the side walls 10 and are provided with gears 71 and 72 meshing together so that the shafts are adapted to rotate in opposite directions. The rotary movement is imparted to gear 71 by means of an idler gear 73 meshing with the first idler 39 already described. The several gears constituting the gear train mounted to the left of the casing are suitably enclosed within a tight cover 75 forming a sort of a gear-box adapted to hold a suitable lubricant and to protect the gears against dirt and other abrasive foreign materials. As shown to advantage in Figures 1, 2 and 6, the comminuting means consist of a plurality of rotors mounted on the shafts 70, each of said rotors including a hub 80 and a number of blades projecting radially therefrom. As shown in Figure 8 the said blades are inclined with respect to the blade of the hub, said inclination being calculated to force the snow or other ice formations to the left, that is: toward the opening 27. Although the said blades 81 are shown arranged in a common plane, it is also within the spirit of the invention that they be slightly offset from each other so as to resemble a worm screw. Thus, the blades 81 having a sharpened edge, their rotation in opposite directions will disintegrate hard snow or ice formations that may be in the path of the apparatus and reduce said for-

mations to a state such that they can be conveniently handled by the worm W for displacement to the right into the duct 50.

The mechanism described so far is actuated by a gasoline engine G acting as a source of power said engine being suitably connected to the driving pinion 40 and supported within the casing C, behind the partition 25 and above the duct 30, on a suitable frame 82. Inasmuch as liquid cooling is convenient for an engine so enclosed, a radiator 85 may be disposed at the front end of the engine and the air of circulation for said radiator drawn through a grill or the like aperture 86 in the back wall 12, the heated air being exhausted through louvers or the like 87 formed in said back wall immediately next to the engine. Immediately below the top 26 of the casing a fuel reservoir 90 can be disposed which may be filled through the filling aperture 91, the said fuel being fed to the engine in any suitable manner. From the foregoing description it should be evident that the mechanism described is self contained, simple and efficient for the purpose in view. It is especially adaptable for the side clearing of city streets where the snow accumulation are generally loaded in suitable vehicles and carted away. Consequently, the jointed arrangement of the outlet elbow at the top of pipe 60 is especially intended for such loading, the same being rotatable with a minimum of friction over the bearings 62 and movable at will by means of the levers 95 extending through slots of the collar 63.

The operation of the apparatus should be fairly obvious from the drawings and description given so far: as the said apparatus is propelled forwardly by the vehicle T, into snow accumulations or banks, the rotating blades 81 will first contact said snow and tend to force the same in the casing by virtue of their inclination. At the same time, the motion of said blades will impart to the snow a leftward movement so as to force the snow through the aperture 27 where the worm W will move it to the right inside the duct 30. The blades 81 are also intended to break, or disintegrate, hard formations in the snow so as to comminute same and render the resultant mass "fluid" enough to be handled by the worm. Thereafter, the snow or comminuted ice is conveyed by the worms W and 51 into the jointed elbow for disposal in any suitable manner.

More specifically, the mechanism of the invention is adapted to move large volumes of snow at relatively low velocity: this is in contrast to the rotary type of snow-plow embodying centrifugal members adapted to project snow with great force at a certain distance. Whereas the last type is particularly useful in the open country, or where adjacent the road to be cleared is available, the present snow conveyor is especially useful for displacing snow from the side of streets and other congested areas to vehicles running alongside the conveyor or in cramped off spaces near the said streets. Due to the structural arrangements disclosed, the operation of the device is efficient, relatively simple, and the direction of snow discharge, as well as its volume, is at all times under perfect control of the operator.

It must be understood that the changes as to the shape, size and arrangement of parts may be resorted to without departing from the spirit of the invention or the scope of the subjoined claims.

Having thus described my invention, I claim:

1. A snow conveyor comprising a casing hav-

ing a back, sides, top and bottom but open at the front, a vertical partition inside the casing behind the open front and substantially parallel with the back, said partition having a large opening at the bottom left thereof, a cylindrical horizontal duct behind the bottom of the partition and opening at one end into the opening of the partition, a shaft rotatable axially in said duct, a worm screw mounted on said shaft, a vertical duct also behind the partition and connecting with the top right end of the horizontal duct, a worm screw rotatable axially in said vertical duct, a gear box between the meeting ends of the horizontal and vertical worms for operatively connecting said worms together, a pair of shafts oppositely rotatable across the casing in front of the partition opening, inclined blades mounted radially on hubs secured to said shafts, and means for driving the horizontal worm and shafts from a source of motive power.

2. In a snow conveyor as claimed in claim 1, radial paddles on the horizontal screw shaft, below the vertical duct and on each side of the gear box, a tube extension projecting out of the vertical duct, means for rotating said tube with

respect to the duct, and a jointed elbow at the free end of said tube.

3. In a snow conveyor as claimed in claim 1, the means for driving the horizontal worm and blades shafts comprising a gear train on the left of the casing, and a cover enclosing said gears.

4. In a snow conveyor as claimed in claim 1, the source of motive power consisting of an internal combustion engine mounted in the casing and behind the partition above the horizontal duct, and means for admitting cooling air thereto.

ARMAND LAMY.
